(57) **CLAIM**

The ornamental design for a wind power generator, as shown and described.

DESCRIPTION

FIG. 1 is a front perspective view of a wind power generator showing my new design;

FIG. 2 is a rear perspective view thereof;

FIG. 3 is a front view thereof;

FIG. 4 is a top plan view thereof;

FIG. 5 is a right side view thereof;

FIG. 6 is a left side view thereof;

FIG. 7 is a rear view thereof;

FIG. 8 is a bottom plan view thereof;

FIG. 9 is a front perspective view thereof, with the fan guards removed for ease of illustration; and,

FIG. 10 is a rear perspective view thereof, with the fan guards removed for ease of illustration.

The broken lines shown represent unclaimed subject matter and form no part of the claimed design.

1 Claim, 10 Drawing Sheets(56)
